US0D1042716S

(12) **United States Design Patent** (10) **Patent No.:** **US D1,042,716 S**
(45) **Date of Patent:** **** Sep. 17, 2024**

(54) **SIGHT**

(71) Applicant: **Aimpoint AB**, Malmö (SE)

(72) Inventor: **Renato Maracic**, Staffanstorp (SE)

(73) Assignee: **AIMPOINT AB**, Malmo (SE)

(**) Term: **15 Years**

(21) Appl. No.: **29/835,575**

(22) Filed: **Apr. 20, 2022**

(30) **Foreign Application Priority Data**

Oct. 21, 2021 (EM) 008732002-0001

(51) **LOC (14) Cl.** **22-01**

(52) **U.S. Cl.**

USPC **D22/109**

(58) **Field of Classification Search**

USPC D16/130, 132, 133, 220; D21/572-574;
D22/108, 109, 110, 199; D26/38, 60

CPC F41G 1/00; F41G 1/32; F41G 1/35

See application file for complete search history.

(57) **CLAIM**

The ornamental design for a sight, as shown and described.

DESCRIPTION

FIG. 1 is a perspective view of a sight showing my new design;

FIG. 2 is a front view thereof;

FIG. 3 is a rear view thereof, from an end opposite that of FIG. 2;

FIG. 4 is a side view thereof;

FIG. 5 is a side view thereof, from a side opposite that of FIG. 4;

FIG. 6 is a top view thereof; and,

FIG. 7 is a bottom view thereof.

The broken lines in the drawings depict portions of the sight that form no part of the claimed design.

1 Claim, 7 Drawing Sheets
